UNITED STATES PATENT OFFICE.

JAMES NIGHTINGALE, OF NEW YORK, N. Y.

QUILLER.

SPECIFICATION forming part of Letters Patent No. 376,607, dated January 17, 1888.

Application filed January 8, 1887. Serial No. 23,723. (No model.)

To all whom it may concern:

Be it known that I, JAMES NIGHTINGALE, of New York, in the county and State of New York, have invented a certain new and useful 5 Improvement in Quillers, of which the following is a specification.

My improvement relates particularly to what I designate as an "individual quiller," meaning a quiller adapted for use with a loom to 10 prepare such quills as shall be required for use in the loom. Certain features of the improvement are, however, applicable to quillers generally.

In the accompanying drawings, Figure 1 is 15 a front view of a quiller embodying my improvement. Fig. 2 is a side view of the same. Fig. 3 is a vertical section taken as indicated by the line $x-x$, Fig. 1, but on a larger scale. Fig. 4 is a side view of certain parts, and Fig. 20 5 is a side view of certain other parts. Fig. 6 is a side view showing a modification of certain parts, certain other parts being omitted or broken away for the sake of clearness. Fig. 7 is an edge view of the same. Figs. 4 and 5 25 are drawn to the same scale as Fig. 3.

Similar letters of reference designate corresponding parts in all the figures.

A designates the frame of the quiller. As shown, it consists, essentially, of a flat part, a , 30 adapted to be secured by bolts B or other means to the frame of a loom or to any other suitable support, and curved end portions, a' , which constitute means for supporting the various parts comprised in the quiller.

C designates a shaft, which in the present example of my improvement occupies a vertical position, and is journaled in the end portions of the frame A. This is the principal shaft of the quiller. It is provided with a fast 35 pulley, A' , and a loose pulley, A^2 . Combined with these pulleys is a belt-shifter, A^3 , consisting of a lever fulcrumed to a pin or stud, a^3 , which extends from the frame A, and having a fork at the end which extends into proximity with the pulleys A' A^2 , and having the other end provided with a lug, a^4 , which extends approximately parallel with the pin or stud a^3 , or, in other words, which extends rearwardly from the lever.

A^4 designates a spring, which is fastened at one end to the frame A, coiled around the stud or pin a^3 , and at the forward end engaged with

the arm of the lever which is provided with the lug a^4 . This spring tends to oscillate the lever so that its fork will shift the belt which is employed in connection with the shaft C onto the loose pulley A^2 . The spring will always adjust the lever so as to cause it to shift the belt onto the loose pulley, except when said spring is prevented from actuating the lever.

D designates an elbow or bell-crank lever fulcrumed at the middle to a pin or stud, d , which is affixed to the frame A. The upwardly-extending arm of this lever is provided with a notch, d' , which is capable of receiving the lug a^4 of the belt-shifter lever. The laterally-extending arm is provided with a slot, through which a rod, D' , loosely extends.

After the belt-shifter lever has been adjusted, by manipulating the arm which is provided with the lug a^4 into such position that its forked end will shift the belt onto the fast pulley A' the lever D will engage with the lug a^4 of said belt-shifter lever, and thereby lock the latter in position. While the belt-shifter lever occupies this position the shaft C will of course be continuously rotated.

The rod D' is provided with two collars, d^2 d^3 , which preferably are adjustable lengthwise 80 of the rod. As shown, they are provided with set-screws d^4 , whereby they may be clamped in position upon the rod after having been properly adjusted. One of the collars, d^2 , is above the arm of the lever D, which receives 85 the rod D' . The other collar, d^3 , is below the lever D. The rod D' normally hangs from the laterally-extending arm of the lever D. It serves as a weight whereby the lever D will have a tendency to rock into a proper position 90 to engage with the lug a^4 of the belt-shifter lever whenever the latter shall be adjusted into such position as to bring its said lug a^4 opposite the notch d' of the lever D. Whenever the rod D' is moved upwardly to such an extent as to bring its collar d^3 into contact with the laterally-extending arm of the lever D the lever D will be rocked in such direction that its notch d' will be disengaged from the lug a^4 of the belt shifter lever. When this happens 95 the spring A^4 will rock the belt-shifter lever so as to cause it to shift the belt from the fast pulley A' to the loose pulley A^2 , in order that the quiller may stop operating.

The manner in which the rod D' is adjusted upwardly for the purpose just mentioned will be fully described hereinafter.

The upper end of the shaft C extends into 5 and through a box-like portion, a², of the frame A, and within said box-like portion the shaft has affixed to it a gear-wheel, C'. This gear-wheel C' engages with a smaller gear-wheel, E', which is affixed to a tubular shaft, 10 to E, forming the shank of a flier, E E'. The arms E² of the flier extend in opposite directions from the shank E, thence downwardly, and thence toward each other, in the ordinary manner. The shank E of the flier is journaled in the box-like portion a² of the frame 15 A, and its gear-wheel E' is contained within said box-like portion.

F designates a frame mounted upon the top of the box-like portion a² of the frame A, and 20 is adapted to receive a shaft, F', upon which is mounted a spool of thread or yarn which is to be formed into a quill.

F² designates a brake consisting of a lever fulcrumed at one end to an extension of the 25 frame F, bearing at the other end upon the thread or yarn which is wound upon the spool, and having hung from it between the ends a weight serving to produce the requisite tension upon the thread or yarn during its passage from the spool. Leaving the spool, the 30 thread or yarn passes through an eye, F³, thence through the hollow or tubular shank E of the flier, and thence through one of the arms of the flier. By the latter it is wound 35 around a quiller-rod to form a quill.

It will be understood that by means of the gear-wheels C' E' the shaft C effects the rotation of the flier. Obviously the rotation of the flier will always bear a fixed relation to the 40 rotation of the shaft C.

G designates the quill-spindle. Each quiller-rod Q* to be wound is fitted to and temporarily secured upon this quill-spindle. The quill-spindle extends through a bearing, a⁵, 45 forming part of the frame A. It will be observed that the quill-spindle extends upwardly and the flier extends downwardly in the present example of my improvement. The quill-spindle does not rotate, but has a longitudinal movement relatively to the flier. At the 50 lower end it has extending laterally from it a pin or projection, G'. To the pin or projection G' is fastened a cord, G². This cord G² passes over a pulley, G³, that is mounted loosely 55 upon a stud extending from the frame A, and at the lower end said cord has a weight, G⁴, fastened to it. The weight G⁴ moves the quill-spindle upwardly, whenever permitted to do so, by the devices which control the movements of said quill-spindle.

I will now describe the means whereby the longitudinal movements of the quill-spindle are controlled.

Near the lower end the shaft C is provided 60 with a worm, H, which is securely affixed thereto. This worm engages with a worm-wheel, H', that is rigidly affixed to a shaft,

H², arranged at right angles to the shaft C and supported in a bearing forming part of the frame A. The shaft H² has also rigidly 70 affixed to it a cam, I, which operates upon a lever, I'. This lever at one end is provided with an anti-friction roller or bowl adapted to bear against the cam I, and at the other end is fulcrumed to a stud, a⁶, affixed to an extension, a⁷, of the frame A.

J designates another lever fulcrumed at one end to a hanger, J'. The hanger J' is pivotally connected at the upper end to the stud a⁶, which forms the fulcrum for the lever I'. The 80 lower portion of the hanger J' is longitudinally slotted, and the lever J is connected to the slotted portion of the hanger by means of a bolt and nut, J². Owing to the slotting of the hanger provision is afforded for adjusting the 85 fulcrum of the lever J, consisting of the bolt J², vertically toward or from the fulcrum a⁶ of the lever I', as may be necessary, in order to secure the desired operation of the lever J. The outer end of the lever J is pivotally connected to the pin or projection G', that extends from the lower end of the quill-spindle. 90

The lever I' has a hanger, I², extending from it. This hanger I² is connected by a bolt and nut with said lever, being preferably slotted longitudinally where the bolt passes through it, so that the hanger may be adjusted to the desired relation with the fulcrum of the lever. The hanger I² is longitudinally slotted throughout the greater portion of its length. This 100 hanger has secured to it a bracket, K. Part of the bracket K extends through the slot of the hanger. A bolt or screw, K', passing through the bracket, then through the slot of the hanger, and also through a nut or block 105 on the opposite side of the hanger, serves to secure the bracket in place upon the hanger. The slotting of the hanger provides for adjusting the bracket to a nicety.

The bracket K supports a shaft, L, which 110 extends approximately at right angles to the shaft C. This shaft L has affixed to it a ratchet-wheel, L'. Adjacent to the ratchet-wheel an elbow or a bell-crank lever, L², is loosely hung. One arm of this lever has a 115 pawl, L³, pivotally connected to it. This pawl is weighted so that it will be caused to engage with the ratchet-wheel. The other arm of the lever has a block, L⁴, loosely mounted upon it, but held in place between a shoulder and a 120 cross-pin. A pin, L⁵, extends through this block L⁴ and also through a block, L⁶, which is loosely mounted upon a rod, L⁷, but held in place thereon by two cross-pins extending through such rod above and below it. The 125 pin L⁵ is loose in the blocks L⁴ L⁶, hence the said blocks are pivotally connected together.

The rod L⁷ extends upwardly to the crank L⁸, which is affixed to the shaft H². This crank is shown as being affixed to the shaft H² 130 through the intervention of the cam I. I mean by this that instead of being directly secured to the shaft it is secured to the said cam, which is a fixture on the shaft. As shown, the crank

has a slotted portion, *h*, which rests upon a block that extends from the forward side of the cam I. A screw, *h'*, passing through the slotted portion of the crank and entering the 5 block of the cam, fastens the crank in place. The wrist or pin of the crank *L*⁸ has loosely mounted upon it a block, *l*. This block is retained in place upon the wrist of the crank by means of a shoulder on one side and a cross- 10 pin on the other side. The rod *L*⁷ has affixed to it a pin, *l'*, which enters the block *l*, so as to be pivotally connected thereto. It will be obvious that the block *l* is therefore pivotally connected to the rod *L*⁷ as well as to the crank 15 *L*⁸. The pin *l'* is provided with a hole whereby it is adapted to fit upon the rod *L*⁷. It is also provided at one end with a set-screw extending into a tapped hole which intersects the hole of the pin which receives the rod *L*⁷. 20 This set-screw serves to secure the pin upon the rod, and provides for the adjustment of the pin into different positions lengthwise of the rod and for securing it when adjusted.

The crank *L*⁸ imparts motion to the rod *L*⁷ and this in turn oscillates the lever *L*², causing the pawl *L*³ of the lever to impart a partial rotary motion of the ratchet-wheel *L*¹, and hence of the shaft *L*. The extent of the motion thus imparted to the shaft *L* may be 30 varied as circumstances may require—as, for instance, to adapt the quiller to threads or yarns of different sizes or to the production of quills of different sizes by adjusting the point at which the crank *L*⁸ is connected to the cam 35 I or shaft *H*² and the point of connection between the pin *l'* and the rod *L*⁷.

On the shaft *L* is a worm, *L*¹⁰, which engages with a worm-wheel, *L*¹¹, mounted upon a shaft, *L*¹². The shaft *L*¹² is journaled in a portion of the bracket *K*, and has affixed to it at the rear end a cam, *M*. The cam *M* is shown as of the kind which is known as a "snail-cam." It operates upon a bearing, *j*, which is affixed to the lever *J*. This bearing is affixed to the 45 lever by means of a screw, *j'*, which passes through a longitudinal slot in the lever. This screw *j'* also secures to the lever a guide, *j*², made in the form of a bowl or roller, which extends through the slot of the hanger *I*².

50 The hanger *I*² is not connected to the lever *J* by means of the guide *j*², but is merely kept in proper relation therewith. Hence in the operation of the quiller the lever *J* may swing relatively to the hanger *I*² without affecting the latter.

55 The cam *I* rotates with sufficient rapidity to allow the quill-spindle to move upward and cause it to move downward in the proper manner for the flier to wind the thread or yarn in layers on the quill. This cam acts on the quill-spindle by actuating the lever *I*', for when the lever *I*' is actuated the cam *M* (which is carried by the lever *I*, owing to the connection of the hanger *I*² with this lever) operates 60 the lever *J* correspondingly, except that, owing to the rotation of the cam *M*, it will impart to the lever *J* a downward motion, which

will be additional to the motion which said lever *J* would receive from the cam *I* alone. The cam *M*, however, moves very slowly, owing 70 to the pawl-and-ratchet movement and the worm and worm-wheel, whereby motion is transmitted to said cam on the shaft *H*², which carries the cam *I*.

The result of the movements imparted by 75 the cams *I* and *M* to the lever *J* is a reciprocating upward and downward movement of the quill-spindle and a progressive downward movement of said spindle. Owing to this the different layers of the thread or yarn wound 80 upon the quill will begin and end at different points in the length of the quill. The shape of the cam *I* is such that the lever *J* will move at different portions of its swing or oscillation at different rates of speed. This will be 85 advantageous, because the winding of the thread or yarn in one direction on the quill will be or form a convolution of quicker pitch that will cross the thread or yarn wound in the reverse direction upon the quill and bind or secure it in position on the quill. The cam *M* makes one rotation for each quill which is wound. As soon as that peripheral portion of the cam *M* which is of greatest projection passes the bearing *j* of the lever *J* the portion 95 of said cam having the least projection comes opposite said bearing, and thereupon the weight *G*⁴ quickly raises the lever *J* until the bearing *j* is brought into contact with the portion of the cam *M* having the least projection. 100 During this movement the quill-spindle will of course have a corresponding upward movement imparted to it. The object of this movement of the lever *J* and quill-spindle is to stop the quiller. I will now describe how this is 105 effected. The pin or projection *G*' at one end is provided with a slot, through which the rod *D*' extends. This rod *D*' near the lower end is provided with a shoulder, *d*⁵. Whenever the quill-spindle is moved sufficiently far downward by the combined action of the cams *I* and *M* the edges of the slot in the pin *G*' will move 110 below the shoulder *d*⁵ of the rod *D*'. It will be observed that this rod *D*' is maintained at a slight incline by the pin or projection *G*'. Obviously, therefore, it has a tendency to assume 115 a vertical position. This tendency causes it to swing in such direction that when the slotted portion of the pin *G*' descends below the shoulder *d*⁵ the rod will swing and its said shoulder will lap over one of the edges of the slot in the pin or projection *G*'. The upward movement of the quill-spindle, which next succeeds the engagement of the pin or projection *G*' with the shoulder of the rod *D*', will cause 125 the rod *D*' to ascend also. Then the collar *d*⁶ of said rod will strike the lever *D* and oscillate said lever, so as to disengage it from the belt-shifter lever *A*³. When this occurs the latter will shift the belt onto the loose pulley 130 and the quiller will stop operating.

The provision for the adjustment of the crank *L*⁸ with relation to the shaft that carries it and with relation to the rod *L*⁷ affords pro-

vision for varying the speed at which the cam M will rotate relatively to the speed of the cam I, and also relatively to the speed of the flier E E'. As the time during which the quiller will remain in operation is dependent upon the time occupied by the cam M in making a rotation, it will be obvious that by affording provision for varying the time in which the cam M will make a rotation I provide for adapting the quiller to operate properly with threads or yarns of different sizes. This is important, because obviously a thread or yarn of smaller size will require more winding than a thread or yarn of large size in order to produce a quill of desired size. And, again, where quills of different sizes are to be made there is advantage in the provision for varying the time in which the cam M will make a rotation.

It is to be observed that the adjusting mechanism which I have described does not vary the operation of all parts of the quiller, but varies the time that the quiller will remain in operation without producing any variation of the speed of the flier or the speed of the longitudinal reciprocations of the quill-spindle.

Although I have shown the cam M as operating upon the quill-spindle through the agency of a lever, J, arranged between it and the quill-spindle, yet it is obvious that the lever is not indispensable to the desired operation of the quill-spindle by the said cam. For instance, if the cam were made sufficiently large it might operate directly upon the pin or projection G'. To facilitate this, this pin might have an extension toward the cam, as shown in Figs. 6 and 7.

What I claim as my invention, and desire to secure by Letters Patent, is—

1. The combination, with a main shaft, of a flier operated by said main shaft, a reciprocating quill-spindle, means, substantially such as described, for raising the quill-spindle when its reciprocations are to cease, a shaft provided with a cam and extending at right angles to said main shaft and deriving motion from said main shaft, a horizontally-extending lever actuated by said cam, a horizontally-extending shaft carried by said lever, mechanism, substantially such as described, between this shaft and the shaft provided with the cam for transmitting motion from the last said shaft to the shaft carried by the lever, a cam also carried by the lever and deriving motion from the shaft which is carried by the lever, and means, substantially such as described, for transmitting motion from said second cam to the reciprocating quill-spindle, between said cam and the quill-spindle, substantially as specified.

2. The combination, with a main shaft, of a flier operated by said main shaft, a reciprocating quill-spindle, means, substantially such as described, for raising the quill-spindle when its reciprocations are to cease, a shaft driven by said main shaft and provided with a cam, a lever actuated by said cam, a shaft carried by said lever, pawl-and-ratchet mechanism deriving motion from said main shaft and trans-

mitting motion to the shaft carried by the lever, a second cam deriving motion from the shaft which is carried by said lever, and means, substantially such as described, between this second cam and the quill-spindle for transmitting motion from said second cam to the quill-spindle, substantially as set forth.

3. The combination, with a main shaft, of a flier operated by said main shaft, a reciprocating quill-spindle, means, substantially such as described, for raising the quill-spindle when the reciprocations are to cease, a shaft deriving motion from said main shaft and provided with a cam, a lever actuated by the cam, a crank upon the shaft which is provided with a cam, a shaft carried by the lever, mechanism, substantially such as described, between this shaft and the crank aforesaid, whereby motion is transmitted from said crank to the said shaft which is carried by the lever, a second cam deriving motion from the shaft which is carried by the lever, and means, substantially such as described, between the second cam and the quill-spindle for transmitting motion from said second cam to the quill-spindle, substantially as specified.

4. The combination, with a main shaft, of a flier operated by said main shaft, a reciprocating quill-spindle, means, substantially such as described, for raising the quill-spindle when its reciprocations are to cease, a shaft deriving motion from said main shaft and provided with a cam, a lever actuated by the cam, a crank-wrist, means, substantially such as described, for adjustably connecting the crank-wrist with the shaft which is provided with a cam, a shaft carried by the lever, mechanism, substantially such as described, between the shaft and the crank aforesaid, whereby motion is transmitted from the crank to said shaft which is carried by the lever, and means, substantially such as described, for transmitting motion from said second cam to the quill-spindle, between the second cam and the quill-spindle, substantially as set forth.

5. The combination, with a main shaft, C, of a flier driven by said main shaft, a shaft, H², also driven by said main shaft, a cam on the shaft H², a lever actuated by said cam, a shaft, L, carried by said lever, a pawl-and-ratchet mechanism between the shaft H² and the shaft L, a shaft, L², deriving motion from the shaft L and provided with a cam, M, a reciprocating quill-spindle, means, substantially such as described, for raising the quill-spindle, and means, substantially such as described, for transmitting motion from the cam M to the quill-spindle, between the cam M and the quill-spindle, substantially as set forth.

6. The combination of a main shaft, C, a flier driven by said main shaft, a shaft, H², driven by said main shaft, a cam affixed to said shaft H², a lever, I', actuated by said cam, a hanger, means, substantially such as described, whereby said hanger is adjustably connected to said lever I', a shaft carried by said hanger, mechanism, substantially such as de-

scribed, between the shaft H^2 and the shaft carried by the hanger, a cam carried by the hanger for imparting motion to the last-named shaft and deriving motion from the shaft which is 5 also carried by the hanger, a reciprocating quill-spindle, means, substantially such as described, for raising the quill-spindle when its reciprocations are to cease, a lever connected with the reciprocating quill-spindle provided 10 with a bearing upon which the cam which is carried by the hanger operates, and means, substantially such as described, for adjusting said bearing into different positions, substantially as set forth.

15 7. The combination, with a main shaft, C, of a flier driven by said main shaft, a shaft, H^2 , driven by said main shaft, a cam on said shaft H^2 , a lever, I', actuated by the cam I, a shaft, L, carried by the lever I', a crank-wrist, 20 means, substantially such as described, for ad-

justably connecting the crank-wrist with the shaft H^2 , a ratchet-wheel on the shaft L, a lever carrying a pawl, a rod connected to the lever which carries the pawl, means, substantially such as described, for adjustably connecting 25 said rod with the crank, a cam, M, carried by said lever and driven by the shaft which is carried by said lever, a reciprocating quill-spindle, means, substantially such as described, for raising said quill-spindle when its reciprocations are to cease, and means, substantially such as described, for transmitting motion from the cam M to the quill-spindle, 30 between the cam and the quill-spindle, substantially as set forth.

JAMES NIGHTINGALE.
